UNITED STATES PATENT OFFICE.

THEODORE V. BREYER, OF NEW PHILADELPHIA, OHIO.

TELEPHONE NOTE RACK AND PENCIL HOLDER.

Application filed February 28, 1927. Serial No. 171,666.

My invention relates to devices for attachment to a telephone to enable the user to have placed before him certain information of a desirable kind, and the invention has 5 for its object to provide a ready and convenient pencil holder and card or memo pad holder, which can be manufactured at a nominal expense, will be light in weight, neat in appearance, and capable of ready 10 attachment to the telephone instrument.

In the drawing:—

Figure 1 is a perspective view of my invention in use.

Figure 2 is a perspective view of my invention per se.

By referring now particularly to the drawing it will be noted that my invention comprises a wire coiled at 1 to constitute a holder or receiver for a pencil, the extreme end of the coil being reduced, as at 2, to prevent the pencil slipping out. The wire at the other end of the coil is extended upwardly, as at 3, and curved into a circular arc at 4, this circular arc portion being flattened for a purpose presently understood.

Following the circular arc portion 4 the wire is bent upwardly and downwardly and back upon itself as at 5 and 6 to provide V-shaped members between which a card or pad 7 may be clipped.

In practice the article will be made preferably of nickled wire so as not to detract from the appearance of the telephone instrument to which it is attached.

In order to install the article on the telephone instrument it is only necessary to loosen the mouth piece of transmitter and slip the curved member 4 over the threaded portion of the same and again tighten up 35 the mouth piece, thus clamping the device between the shoulder of the mouth piece and

the transmitter case and holding it securely in position.

The advantages of my invention lie in the fact that should the user be out of his 45 office and a telephone call comes in the clerk answering the call can jot a notation regarding the call, see Figure 1, and place the note in the clip 5—6 so that when the telephone subscriber returns he will at once see that 50 a call has come in and will know from whom the call came and whether or not he should respond as indicated.

Another use which would be very convenient for the rack would be to provide a 55 printed card with telephone numbers which are called frequently. These could be left stationary and used in connection with the notes that would be placed in the clip. At any time for the convenience of the party 60 he could add new numbers or a new card.

Other advantages of the invention will be clear to those skilled in the art.

What I claim is:

1. An attachment for telephones comprising a wire formed into a coil to constitute a pencil receiver, a flat curved portion adapted to be secured between the transmitter case and the mouth piece of a telephone, and a clip for holding cards, pads and the like.

2. An attachment for telephones comprising a wire having a portion coiled to constitute a pencil receiver, another portion bent into a double V-shape to constitute a card 75 and pad holding clip, and a portion intermediate the first two mentioned portions flattened and bent to fit around the threaded part of the mouth piece and be by it clamped to the telephone transmitter case.

THEODORE V. BREYER.
